CASING FOR AN AMUSEMENT GAME APPARATUS

Harry L. Skelly, Reno, Nev.

Application August 8, 1958, Serial No. 52,141

Term of patent 14 years

(Cl. D34—5)

FIG. 1.

FIG. 2.

FIG. 4.

FIG. 3.

Figure 1 is a front elevation of a casing for an amusement game apparatus showing my new design;

Figure 2 is a side elevation from the left thereof;

Figure 3 is a rear elevation thereof; and

Figure 4 is a side elevation from the right thereof.

The dominant feature of my design resides in the portion shown in full lines.

I claim:

The ornamental design for a casing for an amusement game apparatus, as shown and described.
